UNITED STATES PATENT OFFICE

ERNEST L. SHEPARD, OF FAIRFIELD, MAINE, ASSIGNOR TO KEYES FIBRE COMPANY, INC., OF WATERVILLE, MAINE, A CORPORATION OF MAINE

DESIGN FOR A PACK FOR FRAGILE ARTICLES

Application filed November 18, 1931. Serial No. 41,775. Term of patent 14 years.

To all whom it may concern:

Be it known that I, ERNEST L. SHEPARD, a citizen of the United States, residing at Fairfield, in the county of Somerset and State of Maine, have invented a new, original, and ornamental Design for a Pack for Fragile Articles, of which the following is a specification, reference being had to the accompanying drawing, forming part thereof.

The single figure of the drawing is a perspective view of a pack for fragile articles showing my new design.

I claim:

The ornamental design for a pack for fragile articles, as shown.

ERNEST L. SHEPARD.

CERTIFICATE OF CORRECTION.

Design Patent No. 86,483.

Granted March 8, 1932, to

ERNEST L. SHEPARD.

It is hereby certified that the name of the assignee in the above numbered patent was erroneously described and specified as "Keyes Fibre Company, Inc., of Waterville, Maine, a corporation of Maine", whereas said name should have been described and specified as Fidelity Trust Company, Trustee, of Portland, Maine, a corporation of Maine, as assignee by mesne assignments, as shown by the records of assignments in this office; and that the said Letters Patent should be read with this correction therein that the same may conform to the record of the case in the Patent Office.

Signed and sealed this 17th day of May, A. D. 1932.
